[57] CLAIM

The ornamental design for a child's swing, as shown and described.

DESCRIPTION

FIG. 1 is a perspective view of the child's swing showing our new design;

FIG. 2 is a left side view of the child's swing, the right side being substantially identical;

FIG. 3 is a top view of the child's swing;

FIG. 4 is a front view of the child's swing;

FIG. 5 is a rear view of the child's swing; and

FIG. 6 is a bottom view of the child's swing.
